UNITED STATES PATENT OFFICE.

FLOYD F. JOHNSON, OF BELOIT, WISCONSIN.

VISE.

Application filed November 11, 1926. Serial No. 147,644.

This invention relates generally to improvements in vises or similar gripping tools but is more particularly concerned with pipe vises of the chain type.

5 The principal object is to provide a vise of the kind mentioned which is much quicker in action than those heretofore available by reason of its capacity for operation by a simple swinging movement of a hand lever. 10 The conventional types of vises using a handled nut and screw were slow in action and otherwise objectionable as they were tedious and awkward to operate.

Another important object is to provide in 15 connection with the operating hand lever of the vise by means of which the chain is placed under holding tension, a novel means for locking or clamping the same when the chain is placed under tension whereby the 20 accidental loosening thereof is positively resisted.

Still further objects of the invention relative to the details of construction and arrangement of parts whereby to provide an 25 extremely light and compact device possessing maximum strength and increased capacity will be brought out together with a discussion of the above objects in the course of the following detailed description in 30 which reference is made to the accompanying drawings wherein—

Figure 1 is a side view of a pipe vise constructed in accordance with my invention;

Fig. 2 is a central, vertical, longitudinal section through the vise to more clearly illustrate the construction thereof as well as to better indicate the novel method of operation; and

Fig. 3 is a transverse section taken on the 40 line 3—3 of Fig. 2 looking in the direction of the arrows.

The same reference numerals are applied to corresponding parts in the three views.

The vise comprises a body 10 having a 45 heavy flange 11 thereon by means of which the same may be bolted or otherwise suitably secured as at 12 to a bench, post, or other convenient support indicated at 13. The body has jaw plates 14 secured thereon 50 as by means of screws 15 to provide the gripping teeth 16 for holding an article, such as a piece of pipe indicated at 17. The jaw plates 14 may be renewed whenever the teeth 16 have become worn to such an extent 55 as to afford too little gripping action. Co-operating with the jaw teeth 16 is a flexible

linked chain 18 arranged to be passed about the pipe so as to grip the same securely. The effectiveness of this type of vise is well known and appreciated and, therefore, requires no lengthy explanation. It will suffice to state, therefore, that the wrapping action of the chain about the pipe combined with the gripping action of the teeth positively prevents the pipe from turning. In 60 the event the pipe commences to turn it is caused to roll up the inclined sides of the vise jaws on the teeth 16 and, being confined within the chain 18, is gripped more 65 and more tightly. The operation is the same if it is endeavored to turn the pipe in either direction. Thus, the vise in the case of a tapping operation holds the pipe securely as the die is threaded onto the pipe and the same is true when the die is unthreaded. This general construction, as 70 well as the method of operation thus far described, may be said to be common generally to pipe vises of the chain type and no invention is, therefore, claimed in these 75 broad features excepting in so far as they contribute toward the novel combinations hereinafter described.

The chain 18 has the cross pins 19 in the free end portion of the chain extended beyond the sides of the links 20 to provide trunnions whereby the free end of the chain may be held when the vise is to be operated and the chain is to be placed under holding tension. The free end portion of the chain is arranged to extend through a bifurcated portion 21 on the back of the body 10 so that the ends of the cross pins 19 may be engaged in either one of two pairs of aligned recesses 22 and 23 provided suitably by conforming the back of the body 10 at the bifurcated portion. After a piece of pipe is placed in the vise and the chain is passed about the same and down into the bifurcated portion 21 a cross pin 19 will be entered in whichever pair of recesses is so disposed as to receive the same. In the case illustrated one of the cross pins 19 has been engaged in the lower pair of recesses 22. Obviously, if the pipe were slightly larger or slightly 80 smaller it would become necessary to use the recesses 23 instead. When the free end portion of the chain is held the chain is placed under tension by a simple swinging movement of the hand lever 24 in a clockwise direction as viewed in Fig. 1. The hand lever 24 is conveniently provided with 85

a pipe handle 25 threading therein, as at 26, so that the same may be unthreaded and another handle of greater or smaller length may be substituted. However, the principal purpose in the provision of a removable handle is to enable packing the vise in a kit to be carried about as, for example, on outside jobs, or to enable packing the vise for shipment and storage. The vise with the handle removed takes up very little room and a small packing box will suffice to receive the same with the handle placed in loose. The hand lever 24 has a cylindrical head 27, preferably cast integral therewith, and received in a cylindrical bearing opening 28 extending transversely through the front portion of the body 10. A plate 29 fixed to the end of the head 27, as by means of screws 30, serves to retain the same in its assembled position in the bearing 28. The head 27 is cut away or cored out intermediate the ends of the bearing 28, as indicated at 31, and the body 10 has an opening 32 cored therein in register with the opening 31 so that the inner end of the chain 18 may be entered through the opening 32 into the opening 31 for connection with a pin 33 entered in an opening 34 eccentric to but parallel with the axis of the head 27. The pin 33 by reason of its offset relation in the head 27 is arranged to act as a crank pin to exert a pull on the end of the chain when the hand lever 24 is swung in a clockwise direction as referred to above. The throw of the crank pin, that is its movement from an upper dead center to a lower dead center (see Fig. 2), is preferably equivalent approximately to the distance between the cross pins 19 of the chain 18. Thus it is positively insured that one of the cross pins will be enabled to use either set of recesses 22 or 23 as an abutment to hold the free end of the chain when the same is to be placed under holding tension. In other words, when the free end of the chain is to be held by one of its cross pins in the recesses the crank pin 33 may have to be brought through part of its stroke from upper dead center to lower dead center before the cross pin will find a seat in one of the sets of recesses. The further movement of the pin will then serve to take up what little slack may remain in the chain and place the same under tension so that the pipe or other article placed in the vise will be gripped firmly. The distance between the pairs of recesses 22 and 23 is preferably greater than the distance between adjoining cross pins 19 of the chain, or what amounts to the same thing, greater than the throw of the crank pin 33. In actual practice where the cross pins of the chain are one inch apart and the throw of the crank pin 33 is one inch, that is, it operates on a radius of one-half inch, the distance between the pairs of

recesses 22 and 23 is preferably about one and one-half inches. This relative proportion makes it a simple matter to operate the vise and the action is accordingly much quicker than in the case of any chain type pipe vise of which I am aware. It is especially quicker in its action than that type of vise using a handled nut threading on a screw attached to the end of the chain. This type of vise, besides being slow in action, was particularly tedious and awkward to operate. It will be noted in Fig. 3 that the cross pins 19 at the inner end of the chain are not extended beyond the sides of the links so that the opening 32 may be relatively narrow and the body 10 of the vise will accordingly be that much stronger. The crank pin 33 is preferably removably inserted in the opening 34 and the plate 29 will serve to keep the same in its assembled position in the head. The small opening 35 in register with the opening 34 affords access to the pin 33 from behind the same to enable driving the pin out of the head in the event it becomes necessary at any time to replace the same, or it is desired to disassemble the vise for inspection, cleaning and oiling. By reason of the fact that the load imposed on the head 27 in the tensioning of the chain 18 is concentrated at the middle of the head the latter has an evenly balanced bearing pressure at both ends within the opening 28 and the operation of the hand lever 24 is accordingly made easy as there is no tendency for the head to bind in its bearing when the vise is operated. I will now describe another feature which I have incorporated in my vise and which is particularly advantageous when applied to use in connection with a chain type vise operated by lever action, as above described, whereby the chain when placed under tension serves to lock or clamp the vise to resist any tendency for the chain to loosen. The locking feature is used in connection with the head 27 where the wall of the bearing 28 is arranged to provide a clamping action to grip the head to resist any tendency for the same to turn back once the chain has been placed under tension. It will be observed that the body 10 is slotted from the back through to the bearing opening 28, as at 36. The slot may be formed in the casting of the body 10 but is preferably made by a saw cut. The slot 36 results in the portion 37 of the body 10, which is an integral extension of the wall of the bearing 28, being yieldable. It will be observed that the two pairs of recesses 22 and 23, whereby the free end portion of the chain 18 is held when the chain is to be placed under tension, are provided on the body portion 37. Thus, when the chain is placed under tension by operation of the head 27 with the hand lever 24 the body portion 37 is sprung

slightly, as indicated in a more or less exaggerated degree in Fig. 2, from the dotted line position to the full line position. The springing of the body portion 37 results in 5 a slight contraction of the bearing opening 28 and the head 27 is accordingly locked in position by a clamping action. Obviously, the tighter the vise is pulled the greater will be the gripping action in the bearing 28. It 10 will be noted that the slot 36 is provided approximately on a tangent with respect to the cylindrical bearing opening 28. Thus, on even clamping action practically throughout the circumference of the head 27 is secured. 15 There is obviously little time consumed in closing or opening the vise and the operator is never annoyed with having the vise give under a load imposed on the article held therein. The locking feature, in effect, 20 makes possible the use of a quick operating lever action as herein illustrated.

It is believed that the foregoing description conveys a sufficiently clear understanding of my invention and of its many advantages and other possible applications and adaptations so that anyone skilled in the art to which the invention relates will readily perceive of such variations in design and construction as would naturally suggest 30 themselves after a disclosure of the invention. It will, therefore, be understood that the present embodiment is merely for purposes of illustration and the invention is not to be limited to the specific details shown.

35 I claim:

1. In a gripping tool of the nature of a vise or wrench, a jaw for reception of the pipe or other article to be held, an element providing a complementary holding part 40 whereby to grip the article between it and the jaw, means connected with said element for operating the same and including a part arranged to be moved when said element is tightened or loosened from its hold on the 45 article, and means operated by said element arranged to grip said movable part in the tightening operation and to release the same in the loosening operation.

2. In a gripping tool of the nature of a 50 vise or wrench, a jaw for reception of the article to be held, an element providing a complementary holding part whereby to grip the article between it and the jaw, means connected with said element for operating the 55 same and including a part arranged to be turned to tighten or loosen the hold of said element on the article, and means operated by said element arranged to grip said rotary part in the tightening operation to resist the 60 accidental turning back thereof.

3. In a vise, the combination of a body 65 having a jaw portion thereon for reception of the article to be held, a flexible element to be passed about the article whereby to grip the same between it and the jaw portion,

means on said body for holding the free end of said element, means connected with the other end of said element for tensioning the element, and means actuated by the free end of said element when the same is placed under tension by said last mentioned means to grip the latter to maintain the tension in 70 said element.

4. In a vise, the combination of a body arranged to be fixed to a suitable support and 75 having a jaw portion thereon for reception of the article to be held, a flexible element arranged to be passed about the article to grip the same between it and the jaw portion, means connected with one end of said element to exert a pull thereon to place the element under holding tension, and means provided on a portion of said body to be engaged by the free end of said element for holding the same during tensioning, the said 80 portion of said body providing a clamp for gripping the tensioning means when the flexible element is placed under tension.

5. In a vise, the combination of a body arranged to be mounted on a suitable support 85 and having a jaw portion for reception of the article to be held, a flexible element such as a link chain arranged to be passed about the article to grip the same between it and the jaw portion of the body, an operating 90 handle, a rotary part received in a cylindrical bearing opening provided in said body and arranged to be turned by said handle, an eccentric connection on said rotary part with the end of said flexible element whereby a 95 pull may be exerted on said element by the turning of said rotary part, said body being slotted from one side through to the bearing opening to provide a yielding portion forming an integral extension of one wall of the 100 bearing opening, and means provided on said portion for engagement with the free end portion of said flexible element to hold the element for the tensioning thereof, the yielding portion of said body being arranged 105 to be flexed in the tensioning of said flexible element to distort the wall of the bearing opening to the extent of clamping the rotary part therein.

6. In a vise structure as set forth in claim 115 5, the provision of the slot in the body extending substantially tangentially with respect to the inside wall of the cylindrical bearing opening.

7. In a vise, the combination with a body 120 arranged to be mounted on a suitable support and having a jaw portion for reception of the article to be held, and a flexible element such as a link chain to be passed about the article to grip the same between it and the jaw portion, of means on said body for holding the free end portion of said flexible element, and means connected with the other end of said element for exerting a pull 125 thereon to place the same under a holding 130

5 tension, said means comprising a cylindrical head bearing in a cylindrical opening provided therefor in said body, said head being cut away intermediate the ends of the bearing opening and having an eccentric connection therein with the end of said flexible element, and said body being likewise cut away to permit the extension of the end of the flexible element therethrough into the 10 cut away portion of said head, an operating handle on one side of said head for turning the same, and a plate on the other side of the head to serve with the handle for retaining the head in its bearing opening.

15 8. In a structure as set forth in claim 7 wherein a pin removably inserted in an eccentric opening in the head provides connection with the flexible element, the provision of the plate secured on the end of said head 20 arranged to retain the pin in its assembled position in the head.

9. In a structure as set forth in claim 7 wherein a pin removably inserted in an eccentric opening in the head provides connection with the flexible element, the provision of the plate secured on the end of said head 25 arranged to retain the pin in its assembled position in the head, said head being provided with an opening registering with the opening for the pin, the said opening being of a smaller size than the opening for the pin and serving to afford access to the pin from behind the same to permit the removal thereof.

35 10. In a vise, the combination of a body having a jaw portion for reception of the article to be held, a flexible element to be passed about the article to grip the same between it and the jaw portion, means connected with one end of said flexible element 40 for exerting a pull thereon to place the same under holding tension, and yielding means arranged for detachable connection with the free end portion of said flexible element to hold the same for tensioning.

45 11. In a structure as set forth in claim 10, the provision of means for tensioning the flexible element which comprises a part

50 movable from an upper dead center position to a lower dead center position.

12. In a gripping tool of the nature of a vise or wrench, a jaw for reception of the pipe or other article to be held, an element 55 providing a complementary holding part whereby to grip the article between it and the jaw, means connected with said element for operating the same and including a part arranged to be moved when said element is tightened or loosened from its hold on the article, and means operated in the movement 60 of said movable part arranged to grip the latter.

13. In a gripping tool of the nature of a vise or wrench, a jaw for reception of the 65 article to be held, an element providing a complementary holding part whereby to grip the article between it and the jaw, means connected with said element for operating the same and including a part arranged to be turned to tighten or loosen the 70 hold of said element on the article, and means operated in the turning of said part arranged to grip the latter to resist the accidental turning back thereof.

14. In a vise comprising a body arranged 75 to be mounted on a suitable support and having a jaw portion for reception of the article to be held, a flexible element such as a link chain arranged to be passed about the 80 article to hold the same between it and the jaw portion, means on said body for engagement with the free end portion of said element to hold the same for the tensioning thereof, a crank element connected with the other end of said element and arranged 85 when turned to exert a pull thereon to place the element under holding tension, a lever for turning said crank element, and means for clamping the bearing portion of said crank element to prevent the accidental turning back thereof when the flexible element has been tensioned.

In witness of the foregoing I affix my signature.

FLOYD F. JOHNSON.
